UNITED STATES PATENT OFFICE.

YUJI SUMI, OF SAN FRANCISCO, CALIFORNIA.

DESIGN FOR A COMBINED COAT HANGER AND BRUSH.

Application filed September 8, 1928. Serial No. 28 075. Term of patent 14 years.

To all whom it may concern:

Be it known that I, YUJI SUMI, a subject of the Emperor of Japan, residing at San Francisco, in the county of San Francisco and State of California, have invented a new, original, and ornamental Design for Combined Coat Hangers and Brushes, of which the following is a specification, reference being had to the accompanying drawing, forming a part thereof.

The figure is a front view of the combined coat hanger and brush, showing my new design.

I claim:

The ornamental design for a combined coat hanger and brush as shown.

In witness whereof, I have hereunto set my hand this 28 day of August, 1928.

YUJI SUMI.
